1 James Morton & John Martin, of Philadelphia, Penna.

Assors to

Stuart and Peterson, of the same place.

Letters Patent No 2090-Dated June 13-1865.

Inter-dated May 30-1865.

Design for the Plates of a Stove.

The schedule referred to in these letters Patent and making part of the same
shall show it may concern:

Be it known that we, J. Morton, and J. Martin (assors to Stuart and Peterson), of Philadelphia, County of Philadelphia, and State of Pennsylvania, have invented or produced a new and original design for plates of a cook-stove termed the "Hudson," and we hereby declare the following explanation, with the accompanying drawing to be a full, clear and exact description of the same.

In the drawing.

Fig. 1 represents one of the side plates, and

Fig. 2, the front plate of the stove.

At the edge of the side-plate A, is a plain moulding a, and to the plate is hung a door c, a rib b, extending across the plate above the door. On the plate A, at one side of the door is a panel d, which is enclosed by an ornamental beading e, a similar beading extending round the edges of the door c, and below the panel d, is an oval projection f, which is surrounded by a beading similar to the beading e.

Along the rib b, and at the edge of the plate below the door c, extend a series of ornamental sprigs g.

On the door c, is a panel containing the ornamental foliated figures shown in fig. 1, the panel being surrounded by an ornamental beading similar to the beading e.

2

On the front plate B, base being doors T, T, on which are the ornamental foliated figures, shown in fig. 2, and round the edges of each door extends an ornamental beading, similar to the beading c, on the side plate.

On a projecting portion C of the plate B, above the doors are a series of rounded pipes, and at each of the side edges of the plate is an ornamental beading K.

We claim

The ornamental figures and forms, substantially as represented in and by the accompanying drawing, the whole forming an ornamental design for the side and front plates of the Hudson cook-stove.

Testimony whereof we have signed our names to this specification in the presence of two subscribing witnesses.
